United States Patent Office.

WILLIAM J. LEWIS AND HENRY W. OLIVER, JR., OF PITTSBURG, PENNSYLVANIA.

Letters Patent No. 79,287, dated June 23, 1868.

IMPROVEMENT IN MANUFACTURING BOLSTER-PLATES.

The Schedule referred to in these Letters Patent and making part of the same.

TO ALL WHOM IT MAY CONCERN:

Be it known that we, WILLIAM J. LEWIS and HENRY W. OLIVER, Jr., of Pittsburg, in the county of Allegheny, and State of Pennsylvania, have invented a new and useful Improvement in Bolster-Plates; and we do hereby declare that the following is a full and exact description thereof, reference being had to the accompanying drawings, and to the letters and figures of reference marked thereon.

The nature of our invention consists in rolling a bar of iron, so as to constitute a series of blanks for bolster-plates, of the form hereinafter described.

To enable others skilled in the art to make and use our invention, we will proceed to describe its construction and operation.

In the accompanying drawings, which form part of our specification,

Figure 1 is a face view of a section of a bar of iron rolled out into the desired form for our improvement in bolster-plates.

Figure 2 is a transverse section (full size) of our improvement in bolster-plates.

Figure 3 is a longitudinal section of the bolster-plate, and represents the relation of the two parts of it to the bolster and axle of the wagon.

In constructing our new article of manufacture, viz, bolster-plates, we roll the iron out into bars of the desired length, and of the form represented in the accompanying drawings, which we accomplish by making grooves and recesses in and elevations on the rolls, corresponding to the indentations and elevations in the bolster-plates.

In the drawings, A represents the male and B the female parts of the bolster-plate. The elevation C in the plate A is fitted to a recess, D, in the plate B. The indentations 1 and 2 are guides, for punching out the openings for the "king-bolt." The indentations 3 are guides for making the bolt-holes, for securing the plates to the bolster and axle of the wagon.

The indentations represented by lines X are guides for cutting off the plates at proper lengths. e represents flanges, which are used for the purpose of preventing the plates from moving sideways on the bolster and axle of the wagon.

The advantage of our improvement consists in producing, by rolling, a continuous series of blanks for bolster-plates, of wrought iron, which are of great strength, very durable, and cheap.

Having thus described the nature and construction of our improvement, what we claim as of our invention, is—

A new article of manufacture, viz, iron bars rolled to the shape of a connected series of blanks for bolster-plates, substantially as herein described, and for the purpose set forth.

WM. J. LEWIS.
HENRY W. OLIVER, JR.
